UNITED STATES PATENT OFFICE.

JOHN L. CREVELING, OF NEW YORK, N. Y., ASSIGNEE TO SAFETY CAR HEATING AND LIGHTING COMPANY, A CORPORATION OF NEW JERSEY.

ELECTRIC REGULATION.

1,277,697.

Specification of Letters Patent. Patented Sept. 3, 1918.

Application filed September 22, 1911. Serial No. 650,695.

To all whom it may concern:

Be it known that I, JOHN L. CREVELING, a resident of New York, in the county and State of New York, have invented certain new and useful Improvements in Electric Regulations, as set forth in the annexed specification and drawing, forming a part thereof.

My invention pertains to that class of 10 electric regulation wherein it is desired to regulate a dynamo or generator in a pre-determined manner and has for its particular object to provide means for automatically thus regulating a dynamo.

15 As my invention is particularly applicable to systems of electric distribution wherein a dynamo is used to charge a storage battery and furnish current to lamps or other translating devices, it will be described in 20 connection with such a system.

The drawing is a diagrammatic representation of one type of system embodying the essentials of my invention.

In the drawing, 1 represents a dynamo or 25 generator provided with the usual field coil 2 having in series therewith resistances 3 and 4 indicated as of the carbon pile variety, and it will be obvious that the dynamo may be regulated by proper manipulation 30 of the resistances 3 or 4. The resistance 3 is controlled by the lever 5 normally drawn in an upward direction as by adjustable spring 6 in such manner as to tend to compress the carbon pile 3 and lower the resistance thereof. The lever 5 carries at one extremity a core of magnetic material 7 and thus motion imparted to said core may serve to regulate the generator. The resistance 4 is controlled by the lever 8 normally drawn 40 in an upward direction as by the adjustable spring 9 in such manner as to tend to compress the carbon pile 4 and lower the resistance thereof. The lever 8 is provided at one extremity with a core 10 of magnetic material and thus the generator may be regulated by motion imparted to said core. 11 represents the positive lead of the generator which is carried to one side of the switch 12 which is preferably of the automatic variety adapted to close the circuit when the voltage of the generator is substantially that of the battery and as many such switches are known in the art and the par-

ticular type of switch forms no part of my present invention the presence of one of the well known types is merely indicated diagrammatically. From the switch 12 the lead 11 continues to one side of the switch 13 and is connected with the positive side of the storage battery 14, the negative side of 60 which is connected as by wire 15 with one end of the coil 16 surrounding the core 7 and having its other terminal connected as by lead 17 to the negative brush of the generator. From the switch 13 the wire 18 is 65 carried to one side of the lamps or other translating devices 19 having their negative terminals connected with the wire 20 which is carried to one side of a translation circuit regulator, in this instance indicated as 70 a carbon pile 21 having its opposite terminal connected as by wire 22 with the coil 23, the opposite end of which is in connection with the lead 17. The coils 16 and 23 are so wound that if either be alone energized the same will tend to draw the core 7 75 downwardly against the action of spring 6 and increase the resistance 3, and so wound that current passing through the coil 16 when the battery is being charged will set 80 up a magneto-motive force in the same direction as that set up by the coil 23 when the current is passing therethrough from the lamps or translating devices to the battery. 24 is a coil in shunt across the generator circuit surrounding the core 10 in such manner that when energized it tends to draw the core 10 downwardly and increase the resistance 4. The carbon pile 21 is controlled by the lever 25 normally drawn in a downward direction as by spring 26 and provided at one extremity with the core 27 surrounded by a coil 28 in shunt across the translation circuit.

An operation of the herein shown system 95 comprehending my invention is substantially as follows:

If the dynamo be running at such speed that the electro-motive force be sufficient to charge the storage battery the switch 12 will be closed and current will flow from the generator through lead 11, switch 12, storage battery 14, wire 15, coil 16 and lead 17 to the generator, and I so adjust the spring 6 that when the desired maximum 100 current is flowing through the battery and

coil 16 any appreciable increase above this maximum current will cause said coil to draw the core 7 downwardly against the action of spring 6 and increase the resistance 5 3 in such manner as to hold this desired maximum charging current from being exceeded. If, now, the battery be charged at this maximum rate until its voltage has risen to the maximum voltage desired to 10 have impressed across its terminals, I so adjust the spring 9 that upon any further increase in voltage across the coil 24, the same will cause the core 10 to be drawn downwardly against the action of spring 9 15 in such manner as to reduce the pressure upon the carbon pile 4 and increase the resistance thereof so as to prevent this maximum desired voltage being exceeded by the generator in a well-known manner. If, now, 20 the lamp circuit be closed as by closing the switch 13, current will flow through said switch, wire 18, translating devices 19, wire 20, carbon pile 21, wire 22 and coil 23 to the lead 17, and thence to the generator, the 25 coil 23 being wound in such manner that this current produces a magneto-motive force in the same direction as that produced by the coil 16 and traversed by the battery charging current, and it will thus be obvious 30 that as the translation circuit load is increased less current will be necessary in the coil 16 to prevent the generator output from being exceeded.

Therefore, the battery may be charged at 35 the maximum current desired and as load is thrown upon the translation circuit the current flowing in the coil 23 will lessen the current necessary in the coil 16 in such manner that a desired maximum output of 40 the generator will not be exceeded even though heavy load be placed upon the same when the battery voltage is low. It will also be noted that by proper proportioning 45 of the coils 16 and 23, the generator output may be made to increase as load is thrown upon the translating circuit in a desired manner. That is to say, for example, two amperes increase in lamp load in coil 23 may cause 1 ampere less in the coil 16 and thus 50 the generator output increased one-half the amount of lamp load thrown on, and further, with such proportioning of the coils the generator could never receive more than one hundred per cent. over load, even if 55 the battery coil 16 were cut out altogether, and thus protection is afforded. If the voltage across the translating devices be in excess of that desired to have impressed upon 60 the same, I so adjust the spring 26 that the coil 28 will raise the core 27 and lever 25 and increase the resistance of the carbon pile 21 until the proper voltage is impressed upon the translation circuit; then any tendency to rise above this voltage will cause 65 said resistance to be increased and any fall

in voltage will cause a decrease in resistance in such manner as to hold the voltage upon the translation circuit substantially constant. If the voltage of the generator be below that necessary to charge the battery, 70 the main switch will be opened and current will be supplied by the battery to the translation devices and return through coil 23 and coil 16 to the battery, and it will be noted that the current passing through coil 75 23 is in the same direction as that passing through said coil when the generator was charging the battery. However, that passing through the coil 16 is opposed to the direction of the current flowing through the 80 said coil when the battery was being charged. Therefore, the current passing from the battery to the lamps or translating devices through the two opposed coils will not increase the resistance 3 against the action of spring 6 even though the translation circuit load be quite in excess of the 85 normal generator load, and thus any tendency to prevent the generator from picking out upon starting will be overcome in an 90 obvious manner.

From the foregoing, it will be plain that I have produced a system wherein the generator is automatically controlled to charge a storage battery upon a constant potential 95 circuit, upon certain conditions of the battery, and upon a constant current circuit upon other conditions of the battery. Also, that the output of the generator is automatically varied in a desired manner as current 100 is supplied to the translation circuit and the said current regulation of the generator is affected by the operation of the translation circuit regulator by control of the current in the coil 23.

I do not wish in any way to limit myself to the exact system set forth in this application, merely to illustrate one type of system comprehending the essentials of my invention, for it will be obvious that wide departure may be made without departing from the spirit and scope of my invention which is as set forth in the following claims:

1. The combination with a generator, a storage battery, a battery circuit and a translation circuit, of means for regulating the generator responsive to current fluctuations in the battery circuit, means for regulating the generator responsive to voltage fluctuations and means for modifying the current regulation of the generator affected by current changes in the translation circuit.

2. The combination with a generator, a storage battery and a translation circuit, of means for regulating the generator to charge the battery upon a constant current circuit, means for regulating the generator to charge the battery upon a constant potential circuit and means independent of the

battery current for adjusting the current regulating means and affected by the current in the translation circuit.

3. The combination with a generator, a storage battery and a translation circuit, of means for regulating the generator responsive to voltage fluctuations, means for regulating the generator responsive to battery current fluctuations and means for adjusting the current regulating means responsive to load upon the translation circuit.

4. The combination with a generator, a battery circuit and a translation circuit, of means for regulating the generator responsive to voltage fluctuations, and means for regulating the generator responsive to current in the battery circuit and affected by the current supplied to the translation circuit.

5. The combination with a generator, a storage battery, a battery circuit and a translation circuit, of means for regulating the generator responsive to voltage fluctuations, means for regulating the generator responsive to current changes in the battery circuit and in the translation circuit.

6. The combination with a generator, a storage battery, a battery circuit and a translation circuit, of means for regulating the generator responsive to voltage fluctuations across the same and additional means for regulating the generator responsive to current changes in the battery circuit and in the translation circuit.

7. The combination with a generator, a storage battery, a battery circuit and a translation circuit, of means for regulating the generator responsive to voltage fluctuations across the generator circuit, means for regulating the generator responsive to current changes in the battery circuit and in the translation circuit.

8. The combination with a generator, a battery circuit and a translation circuit, of means for regulating the generator responsive to voltage fluctuations, means for regulating the generator responsive to current fluctuations in the battery circuit and means for affecting the current responsive means in response to current fluctuations in the translation circuit.

9. The combination with a generator, a battery circuit and a translation circuit, of means for regulating the generator responsive to voltage fluctuations across the same and additional means for regulating the generator responsive to current fluctuations in the battery circuit and means for affecting the current responsive means in response to current fluctuations in the translation circuit.

10. The combination with a generator, a battery circuit and a translation circuit, of means for regulating the generator re-

sponsive to voltage fluctuations across the generator circuit, means for regulating the generator responsive to current fluctuations in the battery circuit and means for affecting the current responsive means in response to current fluctuations in the translation circuit.

11. The combination with a generator, a battery circuit and a translation circuit, of means for regulating the generator responsive to voltage fluctuations and means for regulating the generator responsive to current fluctuations comprising current responsive means in the battery circuit and current responsive means in the translation circuit.

12. The combination with a generator, a battery circuit and a translation circuit, of means included in the field circuit only of the generator for regulating the same responsive to current fluctuations, comprising a coil in series with the battery circuit and a coil in series with the generator and the translation circuit, said coils being designed to assist each other.

13. The combination with a generator, a battery circuit and a translation circuit, of means for regulating the generator responsive to voltage fluctuations, and means for regulating the generator responsive to current fluctuations, comprising a coil in series with the battery circuit and a coil in series with the translation circuit.

14. The combination with a generator, a battery circuit and a translation circuit, means for regulating the generator responsive to current fluctuations, comprising a coil in series with the battery circuit and a coil in series with the translation circuit said coils acting to assist each other when the generator is supplying current to the translation circuit.

15. The combination with a generator, a battery circuit and a translation circuit, of means for regulating the generator responsive to voltage fluctuations, means for regulating the generator responsive to current fluctuations, comprising a coil in series with the battery circuit and a coil in series with the translation circuit said coils acting to assist each other when the generator is supplying current to the translation circuit.

16. The combination with a generator, a storage battery, a battery circuit and a translation circuit, of means for regulating the generator responsive to current fluctuations, comprising a coil in series with the battery circuit and a coil in series with the translation circuit said coils acting to assist each other when the generator is supplying current to the translation circuit and to oppose each other when the battery is supplying current to the translation circuit.

17. The combination with a generator, a

battery circuit and a translation circuit, of means forming part of the field circuit of the generator for regulating the same; means for operating the regulating means; and 5 means controlled by current in the translation circuit for modifying the effect of said operating means, by assisting the operating means.

18. The combination with a generator, a 10 storage battery and a translation circuit, of means for regulating the generator to charge the battery so as to maintain a constant current, means for regulating the generator to charge the battery so as to maintain 15 a constant potential, and means for adjusting the current regulating means affected by the current in the translation circuit.

19. The combination with a generator, a 20 storage battery and a translation circuit, of means for regulating the generator responsive to voltage fluctuations, means for regulating the generator responsive to current fluctuations, and means for adjusting the current regulating means responsive to the 25 load put upon the translation circuit.

20. The combination with a generator, a 25 storage battery and a translation circuit, of means for regulating the generator responsive to voltage fluctuations of the generator, 30 means for regulating the generator responsive to current changes in the battery circuit and in the translation circuit.

21. The combination with a generator, a 35 storage battery and a translation circuit, of means for regulating the generator responsive to voltage fluctuations across the generator circuit, means for regulating the generator responsive to current changes in the battery circuit and in the translation circuit.

40 22. In a system of electrical energy including a dynamo electric machine, a storage battery and translating devices; a plurality of regulators therefor embracing means controlled by the voltage of the dynamo, means

jointly controlled by the current from both 45 the dynamo and the battery, and means controlled by the current utilized by the translating devices, all of said means coacting to maintain the voltage of the dynamo and the battery and the current to the translating 50 devices substantially constant for all variations in the system.

23. In a system of electrical energy including a dynamo electric machine, a storage battery and translating devices, two 55 variable resistances in series with the field magnet circuit of the dynamo electric machine, a third variable resistance in circuit with the translating devices and with the dynamo electric machine, electromagnetic 60 means included in the armature circuit of said machine for varying one of said field resistances, electromagnetic means included in circuit with the translating devices for regulating the other field resistance, and 65 electromagnetic means in shunt with the translating devices for regulating the third variable resistance, all of said means coacting.

24. In a system of electrical energy including a dynamo electric machine, a storage battery and translating devices; a compound regulator embracing a plurality of resistances two of which are located in the field circuit of the dynamo and a third in 75 the consumption circuit with the translating devices; together with electromagnetically controlled means therefor adapted to maintain the voltage and current flow of the system relatively constant for changes of speed 80 or voltage in the dynamo, changes of voltage in the battery, and changes of current consumption in the translating devices.

JOHN L. CREVELING.
